UNITED STATES PATENT OFFICE.

EDWIN M. ROSENBLUTH, OF PHILADELPHIA, PENNSYLVANIA.

DESIGN FOR A COMBINATION LAMP AND LICENSE-TAG BRACKET.

41,973.

Specification for Design.

Patented Dec. 12, 1911.

Application filed July 14, 1911. Serial No. 638,597. Term of patent 14 years.

To all whom it may concern:

Be it known that I, EDWIN M. ROSENBLUTH, of Philadelphia, in the State of Pennsylvania, have invented a new, original, and ornamental Design for Combination Lamp and License-Tag Brackets, whereof the following is a specification, reference being had to the accompanying drawing.

In the drawing: Figure I is a plan view of a bracket showing my design. Fig. II is an outer face view of said bracket. Fig. III is an elevation of the left hand end of said bracket as shown in Fig. II.

I claim:

The ornamental design for a combination lamp and license tag bracket, as shown.

EDWIN M. ROSENBLUTH.

Witnesses:

ARTHUR E. PAIGE,
ANNA ISRAELVITZ.
